US00D784078S

(12) **United States Design Patent** (10) **Patent No.:** **US D784,078 S**
(45) **Date of Patent:** **** Apr. 18, 2017**

(54) **BEATER**

(71) Applicant: **SEVERIN ELEKTROGERAETE GMBH**, Sundern (DE)

(72) Inventor: **Calvin Chun Keung Chan**, Sai Wan Ho (HK)

(73) Assignee: **SEVERIN ELEKTROGERAETE GMBH**, Sundern (DE)

(**) Term: **15 Years**

(21) Appl. No.: **29/532,164**

(22) Filed: **Jul. 2, 2015**

Related U.S. Application Data

(62) Division of application No. 29/469,448, filed on Oct. 10, 2013, now Pat. No. Des. 737,097.

(57) **CLAIM**

The ornamental design for a beater, as shown and described.

DESCRIPTION

FIG. 1 is a front view of a beater according to the invention; FIG. 2 is a front perspective view of the beater of FIG. 1; and,

FIG. 3 is a large-scale view of a detail of FIG. 2. The broken lines shown in the drawings are for illustrative purposes only and form no part of the claimed design.

1 Claim, 1 Drawing Sheet
